H. F. JEROLAMAN.
MECHANISM FOR OPERATING FREIGHT CAR DOORS.
APPLICATION FILED MAY 5, 1919.

1,312,180.

Patented Aug. 5, 1919.

UNITED STATES PATENT OFFICE.

HENRY F. JEROLAMAN, OF CHICAGO, ILLINOIS.

MECHANISM FOR OPERATING FREIGHT-CAR DOORS.

1,312,180.

Specification of Letters Patent. Patented Aug. 5, 1919.

Application filed May 5, 1919. Serial No. 294,762.

To all whom it may concern:

Be it known that I, HENRY F. JEROLAMAN, a citizen of the United States, and a resident of the city of Chicago, in the county of Cook and State of Illinois, have invented a certain new and useful Improvement in Mechanism for Operating Freight-Car Doors; and I do hereby declare that the following description of my said invention, taken in connection with the accompanying sheet of drawings, forms a full, clear, and exact specification, which will enable others skilled in the art to which it appertains to make and use the same.

My invention relates generally to improvements in mechanism for operating freight-car doors; and it consists, essentially, in the novel and peculiar combination of parts and details of construction, as herein-after first fully set forth and described and then pointed out in the claims.

The object of this invention is the production of an efficient, and serviceable mechanical means for opening and closing the doors of box cars, which, especially in the, at present, prevailing employment of freight cars having a very large capacity, and consequently increased weight, are rather difficult to open and close without resort to some means for assisting in this opening. This means has generally been a crowbar, and the result of the application of this means may be noticed by the inspection of freight cars that have been in use for some time and show the result and the damages to the car sides and the doors resulting from the use of this instrument of destruction. A further object of this invention is the introduction of means for locking and sealing the car doors to prevent unauthorized entry into the car, said locking means being a part of the mechanism for operating the doors.

Other objects of this invention will herein-after appear.

In order to overcome the hereinbefore mentioned drawback, I construct the mechanism for opening and closing the car door, in the preferred embodiment of my invention, as illustrated in the drawings forming a part of this specification, and in which—

Figure 1 is a side elevation of a car body showing the door in closed condition, and locked, the position of the operating pendulum lever for opening the door being shown in dotted lines. Fig. 2 is a like view show-

ing the door in opened condition, and the mechanical means in position for closing the door. Fig. 3 is a sectional elevation on line 3—3 of Fig. 1. Fig. 4 is a view similar to Fig. 3, drawn on a slightly increased scale to better show the mechanism connected with the door opening and closing means, the pendulum lever shown in dotted lines indicating approximately the limit of the distance which the said lever may be swung away from the door. Fig. 5 is a front elevation of the pendulum lever detached and illustrating the means for locking the car door by the pendulum lever. Fig. 6 is a detail sectional view of a fragment of the car door and one of the projections on the longitudinal bar on the door. Fig. 7 is a sectional plan view of a fragment of the door, the pendulum lever, and the bracket by which the pendulum bar is locked in vertical position. Fig. 8 is an edge view of the said bracket and the lower end of the pendulum lever. Fig. 9 is a detached sectional view of the fulcrum for the pendulum lever.

Like parts are designated by the same characters and symbols of reference in all the figures.

A, in the drawings designates a portion of a box car body of usual construction; and B, the slideable door employed for closing the door opening C, in the car body. There are two of these door openings on each car, one on each side of the car body, and a door for each opening, the car body being usually provided with hangers 12, having track wheels moving on tracks 13, whereby the doors are suspended, and car sills 14, provided with guiding brackets 15, which retain the lower ends of the doors in proper position when closed. There are also secured to the car body stops 16, which limit the distance to which the car doors may be moved in opening; and battens 17, or stops adjacent the door opening C, to limit the closing movement of the door.

As thus far described, the car body and its doors are, as already stated, of usual construction, and it is to this class of cars to which my invention is best adapted for use.

The car sides and the doors being alike in construction, I shall, therefore, refer to them and the operating mechanism, in the singular number.

To the facing 18 of the car body, and above the door B, there is secured a fulcrum

100

105

110

for the depending lever D, which fulcrum comprises a spool G, shown detached in Fig. 9, said spool having two flanges 26, 27, in spaced apart relationship, said spool being 5 secured to the car body A, by a pivot bolt 28, and a multiplicity of screws 29, said pivot bolt 28 extending beyond the face of the flange 27, and carrying loosely at its end a washer 30, the latter flange and the washer 10 being likewise in spaced apart condition to permit the upper end of the pendulum lever D to operate freely upon said pivot bolt.

The pendulum lever D, which is preferably a flat bar, but may also be a round bar 15 flattened at both ends, reaches below the lower end of the door to bring it within easy reach of an operator when standing upon the ground. It has at its upper end a slotted aperture 31, for the reception of the pivot bolt 28, and at its lower end a handle 32, for convenience in handling the pendulum lever from the ground, and somewhat below the middle of its length a second handle 33, for operating the lever from a platform 20 which generally is on the same level as the floor F, of the car body.

Upon the face of the door, preferably slightly above the middle of the door, there is securely fastened a flat bar E, extending 30 entirely across the door and having its ends bent at right angles, as indicated at 21, to engage the vertical edges of the door. From this bar extend a multiplicity of projections 22, 22^a, 22^b, and 22^c, which may be of any desired construction; but which, in the preferred embodiment of my invention, includes a stud bolt 34, securely fastened to the bar E, upon which bolt there is mounted a roller 36, which roller is held in rotatable 35 position upon the bolt 34, by a washer 35, larger in diameter than the roller, to afford shoulders for keeping the pendulum lever in proper position and preventing it from swinging outwardly when being actuated to 40 open or close the door.

In order to lock this pendulum lever in non-operative, depending position, and at the same time to afford means for locking and sealing the door, I provide means, including the following:

Extending from, and secured to, the sill 14, and located below the door, there is a bracket 37, shown in detail in Figs. 7 and 8, which bracket has near the outer end of 55 its horizontal member, an opening 38, and in front of this opening, a transverse slot 39. Near the lower end on the pendulum lever D, there is a transverse slot 40, large enough to permit the pendulum lever being placed 60 over the outer end of the bracket 37.

Upon the pendulum lever there is slidably placed a socket H, which has a laterally extending bar 41, from which extends downwardly, a pin 42, and in front of this pin 65 there is in the bar 41, a transverse slot 43,

the positions of this pin 42 and the slot 43, registering with the positions of the opening 38 and slot 39 in the horizontal limb of the bracket 37.

Let it now be assumed that the door B, 70 in being opened, moves to the right, as shown in Fig. 2. There is placed near the right-hand vertical margin of the door, an angle iron 44, Figs. 1 and 2, against which the pendulum lever bears when the door is 75 closed and the pendulum lever is in vertical position and engaging the bracket 37. This will prevent the door from being opened; and when the socket H with its pin 42 is moved downwardly so that the 80 pin 42 enters the hole 38 in the bracket 37, the pendulum lever D is locked in its depending position, so that when a car seal 45, Fig. 3, is passed through the slot 39 in the bracket 37 and the slot 43 in the socket-bar 41, the car door is also sealed, thereby doing away with the present mechanism for sealing a car, such as staples and hasps, and the like. Instead of this angle iron 44, I may move the projection 22^c on the door 85 somewhat to the right, so that when the pendulum lever is in pendant position, and the door is closed, this lever will bear against this projection and thus serve the purpose of the element 44, a construction 90 which would be perfectly obvious.

Attention is now invited to the fact that the upper end of the pendulum lever D is slotted, the object of which is to permit a certain amount of vertical movement of the 100 pendulum lever, so that the latter will always be in condition to be placed over the bracket 37 when the pendulum lever is to be held in vertical, depending, position. And it is to be noted that the upper end of 105 this lever which is pivoted upon the bolt 28, has some lateral play between the flange 27 of the spool G, and the washer 30, on the bolt. This permits the lower end of the lever to be swung away from the door a 110 certain distance, just sufficient to clear the parts projecting from the door, when the lever is to be employed for opening or closing the door.

The operation of this closure operating 115 mechanism may now be briefly described, as follows:

The car door being closed and the pendulum lever in locked position, the slidable socket H is lifted to disengage its pin 42 120 from the bracket 37, and the lower end of the pendulum lever swung outwardly and to the left, behind the first projection 22^c, and then pulled toward the right to take the first bite, which will move the door B 125 some distance in the same direction. The pendulum lever is then again moved toward the left behind the second projection 22^b, and this step-by-step movement is repeated until the door is entirely opened.

To close the door, the pendulum lever is first placed behind the projection 22, and then the manipulation of the lever repeated, as hereinbefore stated, until the door is closed; and the pendulum lever placed onto the bracket 37 and the socket H lowered to cause the pin 42 to engage the hole 38 in the bracket 37.

The object of the roller 36 on the stud bolt 37, shown in Fig. 6, is to reduce friction on the pendulum lever when moving the door, as far as possible; and the projecting flange 35 serves to prevent the pendulum lever from slipping off the roller when being operated.

While I have hereinbefore described the preferred embodiment of my invention, I desire it to be understood that I am aware that changes may be made in the details of construction, to adapt this invention to the different freight cars now in use, and that parts may be omitted without departing from the scope of my invention, as defined in the appended claims.

Having thus fully described this invention, I claim as new, and desire to secure to me by Letters Patent of the United States—

1. Mechanism for opening and closing the doors of box cars, comprising, in combination, a car body, a slidable door on said car body, a fulcrum secured to said car body above said door, a lever pivotally connected to said fulcrum, a bar, said bar being longitudinally secured to the face of the door above the middle of the door, said bar having a series of spaced apart projections which said lever is constructed to engage to open and close the door by a step-by-step movement of said lever, and means connected with said fulcrum to prevent outward movement of said lever beyond a predetermined distance, said latter means including a spool, said spool having at its outer end a flange, a bolt passing through said spool and projecting therefrom, and a washer at the outer end of said bolt, said washer being spaced from said flange sufficiently to permit said pendulum lever to attain a position slightly inclined to the axis of said bolt.

2. Mechanism for operating the doors of freight cars, comprising, in combination, a car body, a slidable door on said car body, a fulcrum secured to said car body above said door, a lever pivotally connected to said fulcrum, a bar, said bar being longitudinally secured to the face of the door, said bar having a series of spaced apart projections which said lever is constructed to engage, said pendulum lever being constructed to swing pendulum-fashion across the face of the door and over said projections, said projections including a stud bolt fixed to said bar, a roller on said stud bolt, and a washer at the front end of said stud bolt, said

washer being larger in diameter than the said roller to prevent said lever from sliding off said roller.

3. Mechanism for opening and closing the doors of box cars, comprising, in combination, a car body, a slidable door mounted on said car body, a fulcrum secured to said car body above said door and in line with one edge of the door opening in said car body, said fulcrum including a fixed pivot bolt, a spool on said pivot bolt and fixed to said car body, said bolt extending beyond said spool, and a washer at the outer end of said bolt, a lever rotatably and slidably mounted on said bolt between said spool and said washer, a series of projecting elements on said door in horizontal, spaced apart, relationship, said lever being constructed to engage said projecting elements, one at a time, to open and close said door by a step-by-step movement of said lever, said lever having its upper end slotted to engage the projecting part of said pivot bolt.

4. Mechanism for opening and closing the doors of box cars, including, in combination, a car body having a door opening, a door slidably mounted on said car body for closing said opening, a fulcrum on said car body above said door, a pendulum lever pivotally mounted on said fulcrum at its upper end, a series of protuberances in spaced apart relationship on said door which said pendulum lever is constructed to engage alternately to move said door by a step-by-step movement of said pendulum lever, and coacting means on said door, on said car body, and on said pendulum lever for locking the door by said pendulum lever.

5. Mechanism for opening and closing the doors of box cars, including, in combination, a car body, a door slidably mounted on said car body, a fulcrum on said car body above said door, a pendulum lever, said pendulum lever being mounted on said fulcrum at its upper end, a series of horizontally disposed projections on said door which said pendulum lever is constructed to engage to open and close said door by a step-by-step movement of said pendulum lever, and coacting means on said door, on said car body, and on said pendulum lever for locking said door by said pendulum lever, the means for locking the door including a stop on said door, a slidable socket at the lower end of said pendulum lever, and a bracket extending from said car body below said door which said pendulum lever is constructed to engage.

6. Mechanism for opening and closing the doors of box cars, including, in combination, a car body, a door slidably mounted on said car body, a fulcrum on said car body above said door, a pendulum lever pivotally mounted on said fulcrum and constructed to swing, pendulum-fashion, in front of said door, a series of aligned projections on the face of the

door, in spaced apart relationship, which said pendulum lever is constructed to engage, one after the other, to move said door by a step-by-step movement, and coacting means on said door, said car body, and said pendulum lever for locking said door in either an open or a closed position, said means including a stop on the car door, a sliding socket on said pendulum lever, and a bracket extending from said car body be-

low said door, said sliding socket having a downwardly extending pin, said bracket having an opening which said pin is constructed to engage, the lower end of said pendulum lever having a transverse slot to engage said bracket. 15

In testimony that I claim the foregoing as my invention, I have hereunto set my hand.

HENRY F. JEROLAMAN.
